F. M. BUTLER

APPARATUS FOR STORING DISHES

Filed April 23, 1925

Inventor:
Fannie M. Butler
George L. Wright
Atty.

UNITED STATES PATENT OFFICE.

FANNIE M. BUTLER, OF HINSDALE, ILLINOIS.

APPARATUS FOR STORING DISHES.

Application filed April 23, 1925. Serial No. 25,195.

This invention relates to apparatus for storing dishes. In many large manufacturing and industrial cities, great quantities of soot, dust and the like, are released into the air and eventually find their way into dwellings, where they form deposits upon various household articles, and such deposits are particularly obnoxious in the case of dishes of various kinds, 10 glassware, etc., and this condition is much aggravated by soot and dust which is released incident to the operation of heating apparatus within the dwellings, which also find their way into the living quarters, and become deposited upon the dishes, all of which necessitates frequent and thorough cleansing of the dishes not only after their use, but immediately prior to subsequent use. This results in a great increase in the labor necessary to keep the dishes clean for the reason that the same of course must be cleansed immediately after use, placed away in suitable cabinets or pantries, where in a short time they accumulate deposits as above referred 20 to, and consequently must be again washed or cleansed before they can be used. In many homes expensive delicately tinted and richly ornamented dishes are used, and the frequent cleansing and scouring necessary to render such dishes fit for use, under conditions above referred to, result in injurious abrasion and defacement of the decorations, causing a decrease in the value and ornamental effect of the dishes.

An object of my invention is to provide a method and apparatus for handling dishes wherein a plurality of receptacles are provided which are arranged in a predetermined order, and in each of which a group or collection of dishes of like character are adapted to be placed, so as to facilitate the handling thereof, each of such receptacles providing means for preventing deposits of dust and soot, and the like thereon, so that when the dishes are once washed or cleansed, and placed in the receptacles, they are protected from becoming soiled over any period of time desired, and when it is again desired to use the same, they may be removed from the receptacles in as cleanly a condition as when placed therein and used without additional cleansing thereof.

Another object of the invention is to provide a receptacle of a novel character for use in connection with the dishes which is pro-

vided with means for rendering the same proof against the entry of dust, soot and the like, and which is made up of light fibrous material, so as to be easily handled, and is of such a size as to fit between the shelves ordinarily provided in cabinets and pantries.

Other and further objects of the invention will more fully and clearly appear from the description and claims hereinafter following.

In the drawings Figure 1 is a front elevation of a suitable support, such as cabinet or pantry shelves, showing a plurality of dust-proof elements arranged in a predetermined order thereon. Figure 2 is an enlarged perspective view of a dust-proof receptacle of the character utilized in connection with my invention. Figure 3 is a fragmentary view of the forward top portion of the receptacle, showing in section, a portion of the top wall and the door in closed position, and illustrating the means utilized for rendering the door dust-proof. Figure 4 is a fragmentary view showing the side wall and door of the receptacle, and illustrating the means associated therewith for rendering the receptacle dust-proof.

In the drawings 5 represents a fragment of a suitable cabinet or pantry in which are mounted shelves 6 and 7. Mounted upon the shelves 6 and 7, is a plurality of receptacles 8, of different sizes, each of which is adapted for the reception of approximately a dozen dishes of similar character. The receptacles 8 are of a peculiar construction which will now be described, and are arranged upon shelves 6 and 7 in a particular predetermined order which will be hereinafter referred to.

Each of the receptacles 8 is made up of light, thin, strong, fibrous waterproof material, and the same is assembled in a manner which renders the same dust-proof, and of a strong and durable construction, the material being of such a character that when formed it will retain such form. The top wall 9, the rear wall 10, and the bottom wall 11, are all formed in one piece, the material being bent so as to dispose the top and bottom walls substantially perpendicularly to the rear wall, each side edge of the top, bottom and rear walls being provided with inturned flanges 12, such flanges being beveled as shown at 13 and 14 to permit the bending of the single piece into the desired form. The top wall 9 adjacent the forward end is provided

with a corrugation or depression 9' for co-operation with a similar depression or corrugation in the door member hereinafter referred to. The side walls 15 and 16 are disposed upon the inner sides of the flanges 12 on the top, rear and bottom walls, and the adjacent edges of the side members 15 and 16 are secured to the flanges 12 by a plurality of rivets 17. The interior of the receptacle is preferably lined with a suitable dust-proof fabric 18, which extends over the junctures of the side walls with the top, rear and bottom walls, so that no dust or similar substance can possibly enter the receptacle or 15 container through any crevices which might be present at the points of juncture. The forward edges of the side walls 15 and 16 are provided with inturned flanges 19 and 20, and each of such flanges is provided with an in- 20 wardly extending corrugation 21 extending vertically throughout the extent of the related flange, for a purpose which presently will be made apparent.

A door 22 is provided for closing the open 25 end of the receptacle, the door being formed of the same material as the body of the receptacle, such door comprising the main wall portion 23, at the side edges of which are formed inturned flanges 24, which are spaced apart 30 a distance very slightly greater than the overall width of the receptacle. The wall 23 at the bottom edge has secured thereto by means of a plurality of rivets 25^a, a flexible strip 26, preferably of leather, the edge of the strip 35 opposite to that fastened to the door, being fastened to the bottom wall of the receptacle by a plurality of rivets 26^a. The wall 23 of the door upon the inner side thereof has fastened thereto by adhesive or other suitable 40 means, suitable dust excluding fabric 27, preferably forming a continuation of the lining on the surface of the receptacle, the side edges of such fabric extending beneath the bottom portions of the inturned flanges 19 on the side 45 walls 15 and 16. In this connection the fabric 27 may be a separate piece if desired, either arrangement serving to seal the hinged portion of the door against entry of dust and the like as will be readily appreciated. Ad- 50 jacent to the flanges 24 and extending parallel therewith, are corrugations 25, which when the door is closed are adapted to register with the corrugations 21 formed in the inturned flanges of the side walls 15 and 16.

55 Secured to the upper edge of the wall 23 of the door member is a securing flap 28, such flap being hingedly connected to the edge of the wall 23 of the door by a flexible hinge member 29 similar to the hinge member 26 on the bottom of the door, such hinge member 60 preferably being of suitable flexible material such as leather, one edge being secured to the door wall 23 by means of rivets 30, and the other edge being secured to the flap by 65 rivets 31. The top portions of the flanges 24

are beveled as indicated at 32, and the flap 29 is provided with inturned flanges 33 which are also beveled to permit swinging movement of the flap, the flanges 33 of such flap being spaced apart sufficiently to snugly engage the side walls of the receptacle when the door is closed. The flap is provided with a corrugation 33' adapted to register with the corrugation 9' in the top wall 9 of the receptacle. The top wall 9 of the receptacle is provided with suitable pivoted latches 35 adapted to snap over keepers 36 on the flap 33 so as to hold the door in closed position.

70 By this arrangement it will be apparent that I have provided a receptacle of a simple 80 and efficient character which is light in construction and easily handled, and which includes means for rendering the same absolutely dust-proof. It will be appreciated that the hinged portions of the door are so arranged as to render the same dust-proof, and due to the provision of the flanges on the door and receptacle and to the registration of the corrugations in the door and receptacle, dust is absolutely excluded from entry into 90 the receptacle when the door is closed.

95 As before stated my invention also includes a method of arranging a plurality of different types of dishes for efficient and cleanly handling. Said method consists in providing a 100 plurality of dust-proof receptacles of different sizes of the type heretofore described in detail, and arranging the receptacles upon the shelves 6 and 7 in a predetermined order, that is, a relatively large receptacle 8 will be 105 provided for a group of soup plates, and the receptacle appropriately labeled as shown in the drawing; the next successive receptacle being of a similar character and smaller size, and in which may be placed a group of appetizer plates for instance, and the receptacle 110 appropriately labeled; the next receptacle may be of a size to accommodate meat course plates, and so on, the invention contemplat- 115 ing providing a receptacle of a suitable size for a group of each type of dishes, the receptacles being arranged in a predetermined order, such for example, as the order in which the same are adapted to be successively used in a course dinner. By this arrangement 120 the dishes may be stored for long periods of time, without being soiled, and when it is desired to use the same, the required dishes may be readily located and easily withdrawn from the receptacles, the remaining dishes which 125 are not withdrawn of course being preserved against soiling until used. This arrangement thus affords a novel method of handling the dishes with a minimum of time and effort necessary to keep the same clean, and facilitates locating and selecting the particular types of dishes which it is desired to use.

130 While I have herein shown and described what I now consider the preferred manner of carrying out my invention, the same is

merely illustrative and I contemplate all changes and modifications that come within the scope of the claims appended hereto.

I claim:

5. 1. A receptacle of the character described, comprising top, rear, bottom and side walls, the top wall being provided with a pressed integral corrugation, and the side walls provided with inturned flanges having integrally 10 pressed corrugations therein; a door hingedly connected to said receptacle, said door being provided with integrally pressed corrugations adapted to register with the corrugations in the portions of the receptacle 15 when said door is closed; and means for holding said door in closed position, said door being provided with dust-proof material which extends over the related corrugations, and is adapted to be disposed between the registering corrugations when the door is in 20 closed position.
2. A receptacle of the character described, comprising top, bottom, rear and side walls, the top wall being provided with an integrally formed corrugation, and said side walls having inturned flanges provided with integrally formed corrugations; a lining on the interior of said receptacle for excluding dust therefrom; a door having a flexible 25 hinge member connecting the same to said receptacle, the lining of said receptacle being provided with an extension which is secured over the hinge connection and to the door, said door also being provided with integrally 30

formed corrugations adapted to register with the corrugations in the top and side walls of the receptacle when the door is closed, the lining extending over the corrugations in said door; and means for holding said door in 35 closed position.

3. A dish receptacle, comprising top, rear, and bottom walls, the top, rear and bottom walls consisting of a single member bent to form and having inturned flanges along its edges; side walls secured to said flanges, 40 said side walls being provided with inturned flanges, each of which has pressed therein an integral corrugation, said top wall also being provided with an integrally formed corrugation; a door for closing the open end of said 45 receptacle, said door being hingedly connected to the bottom wall of said receptacle, and having integrally formed corrugations adapted to register with the corrugations in the portions of the receptacle when said door is 50 closed, said door including flanges adapted to lap past the walls of said receptacle; dust-proof lining for covering the junctures of said receptacle, said lining being arranged over the hinged connection of said door with 55 said receptacle and being interposed between the surfaces of the registering corrugations when said door is closed.

In witness that I claim the foregoing I have hereunto subscribed my name this 13th 60 day of April, 1925.

FANNIE M. BUTLER.
